UNITED STATES PATENT OFFICE.

CHARLES M. HIBBETS, OF WASHBURN, TEXAS.

GUARD-RAIL.

No. 831,553.

Specification of Letters Patent.

Patented Sept. 25, 1906.

Application filed January 29, 1906. Serial No. 298,516.

To all whom it may concern:

Be it known that I, CHARLES M. HIBBETS, a citizen of the United States, residing at Washburn, in the county of Armstrong and State of Texas, have invented certain new and useful Improvements in Guard-Rails, of which the following is a specification.

This invention relates to certain improvements in guard-rails, and is particularly designed for use in connection with the improvements in switches for which Letters Patent of the United States, No. 797,772, were issued to me August 22, 1905.

The patented invention comprehends a railway-switch mechanism embodying means for preventing derailment of a train should the switch be left in a neutral or split position, such means including an incline over which the car-wheels are designed to travel from the split switch back to the main-line rails and also including in connection with said incline a guard-rail designed to form a bearing-surface for the opposite car-wheels and having a diagonal portion converging in a direction from the switch-point to the opposite main-line rail, so as to direct the car-wheels back to the main track and insure that they shall be properly positioned on the main-track rails.

My present invention contemplates particularly improvements in the construction of the said guard-rail designed to direct the car-wheels back to the main-line rails; and it consists of certain improvements hereinafter fully described, and particularly pointed out in the appended claim.

For a full description of the invention and the merits thereof and also to acquire a knowledge of the details of construction of the means for effecting the result reference is to be had to the following description and accompanying drawings, in which—

Figure 1 is a plan view of a railway-switch embodying the patented improvements and the improvements of the present invention. Fig. 2 is a perspective view thereof. Figs. 3 and 4 are cross-sectional views illustrating particularly, on a larger scale, my improved construction of guard-rail embodied in the present invention.

Corresponding and like parts are referred to in the following description and indicated in all the views of the drawings by the same reference characters.

Referring to the drawings, the numeral 1 designates the main rails of the tracks, and 2 the side rails.

3 indicates the siding switch-point, and 4 the main-line switch-point. Contiguous to the butt-end of the main-line switch-point 4 the adjacent main rail 1 is provided with an incline 5, designed to direct the wheels of a train back onto the main-line track-rails should they be liable for derailment by entering the switch with the switch-point in the neutral position, and to assist in this operation the side rail 2 where it connects with the butt-end of the switch-point 3 has connected to it a guard-rail 6, which extends from the side rail 2 in a diagonal direction toward the adjacent main-line rail 1 and draws the car-wheels laterally when some of them have ridden over the incline 5, so that they will be properly directed back upon the main-line rails 1 and derailment will be avoided. In general construction the above describes the patented improvements before referred to.

In the present embodiment of the invention the guard-rail 6 is provided with a thickened web 7, designed to fit snugly against the web of the adjacent main rail 1 throughout the length of the said guard-rail both in the parallel portion of the latter and the diagonal portion thereof, so that snow and ice will be prevented from packing between the main-line rail and the guard-rail. The inner surface 8 and lower oblique portion 8^a of the guard-rail are of such size and shape that they will accurately fit the web and base-flange of the main-line rail, and the thickness 9 of the web 7 of the guard-rail is of course determined at the different portions thereof by the desired distance between the head or tread of the main-line rail 1 and the head 9 of the guard-rail 6. As shown particularly in Fig. 4, the upper surface 10 of the guard-rail 7 is somewhat countersunk, so as to give passage-way for the flange of a wheel where the ball of the rail is not thick enough to clear the flange. The head 9 of the guard-rail 6 is cut away at the sides adjacent the main rail, as indicated at 11, so as to form a preferably flat portion, which is advantageous, in that the foot of a person is not likely to be caught between it and the adjacent main rail.

By my improved construction of guard-rail the liability of snow and ice packing between the guard-rail and the adjacent main-

line rail is reduced to a minimum, and thereby the efficient operation of the patented switch mechanism before mentioned is insured under all weather conditions.

- 5 In the manufacture of the guard-rail and main rail embodying the features of my invention both are preferably rolled in one solid piece and in the shape shown by Figs. 3 and 4 from the first joint back of the heel of
- 10 the switch-points on the main-line rail. While Figs. 3 and 4 indicate that the guard-rail and main-line rail are formed separately, yet the integral construction just described is the preferred one, because there will be no
- 15 noise or rattling when trains are passing over the rails at that point and there will be no transverse bolts to become worn or broken. Otherwise the same result may be obtained by using the ordinary rail as made for regular
- 20 use and by rolling the block to the exact shape to fill the space between the rails. In some localities the guard-rail constructed as

in my patent above referred to will be the most useful and practical.

Having thus described the invention, what 25 is claimed as new is—

Switch mechanism of the character described embodying an incline designed to direct the wheels of a train back on the main track, and a guard-rail opposite the said incline and provided with a diagonal portion designed to draw the wheels laterally so as to seat them upon the main-line rails, said guard-rail being provided with a thickened web throughout its length filling the space 35 between the outer side of said web and the adjacent side of the adjacent main-line rail.

In testimony whereof I affix my signature in presence of two witnesses.

CHARLES M. HIBBETS. [L. s.]
